CLOTH BOLT TICKET

Lawrence Davis, Walpole, Mass.

Application March 1, 1933, Serial No. 659,060

4 Claims. (Cl. 40—20)

This invention relates to tickets, tags, and the like, adapted to be used on bolts of cloth usually for the purpose of designating the nature of the goods and sometimes, also, to carry other information relating to them.

It is the usual custom to secure such a tag or ticket to the fabric at the end of the bolt by means of a string or thread. After the bolt is placed on the shelf of the retail store, the ticket usually is tucked into the end of the bolt but is left attached to it so that it can be referred to whenever necessary to determine the grade or quality of the goods, the name of the manufacturer, or any other information which the ticket may carry.

15 The present invention aims to improve tickets of this general character with a view to providing a more useful article and avoiding much of the annoyance incident to the use of prior devices of this type.

20 The nature of the invention will be readily understood from the following description when read in connection with the accompanying drawing, and the novel features will be particularly pointed out in the appended claims.

25 In the drawing,

Figure 1 is a plan view of a ticket embodying this invention;

Fig. 2 is a perspective view of the ticket shown in Fig. 1 but illustrating it in a folded condition;

30 Fig. 3 is a perspective view of a part of the rear section of the ticket shown in Figs. 1 and 2;

Figs. 4 and 5 illustrate ways in which the ticket may be used; and

Fig. 6 is a sectional view on the line 6—6, Fig. 5.

35 Referring first to Figs. 1, 2 and 3, the ticket there shown is made of cardboard or similar relatively stiff sheet material and it consists of a front section 2 and a rear section 3. These sections may take various shapes and dimensions,

40 but they are preferably so designed that they can be cut simultaneously out of sheet material and then folded at one edge, somewhat as indicated in Fig. 2, it being understood that the sections normally are held one against the other instead of 45 being partly separated as in Fig. 2. It is contemplated that the front face of the section 2 will bear the usual information contained on such a ticket, and that, in addition, it will carry advertising matter, the nature of which necessarily

50 will depend upon the character of the goods. The rear section 3 has a tongue 4 cut from the material thereof, as clearly shown in the drawing, and preferably is scored along the uncut edge to facilitate folding the tongue downwardly at right angles to said section, as shown in Fig. 3. Pref-

erably the upper margin of this tongue is gummed, as shown at 5 in Fig. 1. The back face of the rear section 3 may also bear printed directions explaining the manner in which the ticket is to be applied to the goods.

At the end of the ticket opposite to the folded edge 6 registering holes 7 are punched to receive a string, ribbon, or the like, indicated at 8.

In using this ticket it is contemplated that the string will be fastened to the fabric at the end of the bolt, as has been customary heretofore, this string being brought through the folds of the wrapper 10, Fig. 4, so that the ticket will be exposed at the end of the package and outside the wrapper when the goods are wrapped preparatory to shipment. After the goods have reached the retail store and the wrapper is removed, the ticket still remains attached to the goods by the string. At this time, however, the tongue 4 is bent downwardly at right angles to the main body of the ticket, the gummed strip 5 is moistened, and the tongue is forced into the end of the bolt between the cloth board 12 and the fabric wound on said board. The pressure of the cloth will hold the tongue in this position while the gum hardens, after which the ticket will be secured firmly to the bolt with the main body of the ticket resting against the end face of the bolt, as shown in Figs. 5 and 6. The ticket remains in this position indefinitely, or until most of the fabric has been removed from the cloth board.

With this construction the ticket can always be seen at the end of the bolt and it is unnecessary for the salesman to pull the ticket out of the end of the bolt in order to see the information printed on it, as has been necessary with prior tags or tickets. The present construction, therefore, not only avoids this annoyance and inconvenience, but since the ticket is always in plain view, the salesman can see at a glance exactly the nature of the goods wound on the bolt and his selection of the bolt containing the desired fabric therefore is facilitated. If the tongue should accidentally become loosened from the bolt, the ticket still would be secured by the string so that it would not be lost. In addition, the face of the ticket can be printed in an attractive design which may or may not bear advertising matter, but which will contribute to the attractive presentation of the goods.

While I have herein shown and described a preferred embodiment of my invention, it will be evident that the invention may be embodied in other forms without departing from the spirit or scope thereof.

Having thus described my invention, what I desire to claim as new is:

- 5 1. A cloth bolt ticket having front and rear sections, and having a string extending through said sections, and effective to secure the ticket to a bolt of fabric, said ticket including a tab projecting rearwardly therefrom and adapted to be inserted between the cloth board and the fabric wound thereon to secure the ticket against one end of the bolt.
- 10 2. A cloth bolt ticket folded to provide front and rear sections, the front section bearing information relating to the goods, and said rear section having a cut-out tongue integral therewith and adapted to be inserted between the cloth board and the fabric wound on said board to secure the ticket against the end face of the bolt.
- 15

3. A cloth bolt ticket folded to provide front and rear sections, both of said sections being punched to receive a string, and the rear section having a tongue punched therefrom but secured thereto, the margin of said tongue being 5 gummed.

4. A cloth bolt ticket comprising relatively stiff sheet material folded to provide front and rear sections, said sections having holes punched therethrough adjacent to the ends to register 10 with each other when the ticket is folded, a string threaded through said registering holes for anchoring said ticket to the fabric of the bolt, said rear section having a tab rigid therewith and adapted to be inserted between the cloth 15 board and the goods wound thereon to secure the ticket against the end face of the bolt.

LAWRENCE DAVIS.
